CLAIM

The ornamental design for a cellular phone remote control device, as shown and described.

DESCRIPTION

FIG. 1 is a rear, top, and left side perspective view of a cellular phone remote control device showing our new design;

FIG. 2 is a top view thereof;

FIG. 3 is a bottom view thereof;

FIG. 4 is a left side view, the right side being a mirror image thereof;

FIG. 5 is a front view thereof; and,

FIG. 6 is a rear view thereof.

FIG. .1.

FIG. .2.

FIG. .3.

FIG. .4.

FIG. .5.

FIG. .6.
